ABSTRACT

The dental handpiece disclosed herein has a housing extending along a longitudinal axis. An air turbine rotatable about a transverse axis is disposed within the housing and fed with air through a hollow rod in the housing and rotatable about the longitudinal axis so that an inclined nozzle at the rod end can drive the turbine in either direction. The turbine drives a transverse friction shaft engaging a friction disc on a drive shaft journaled in the housing for rotation about the longitudinal axis. Spent air may exhaust directly to atmosphere or through a hand controlled port or through a port throttled according to drive shaft speed. A externally releasable chuck in the housing is driven by the drive shaft.

DENTAL HANDPIECE

It is particularly an object of the present invention to provide a dental handpiece in which the tool-holding chuck is driven by means of air under a super-atmospheric pressure.

Another object of the invention is to provide means for compactly locating an air turbine within a dental handpiece.

A further object of the invention is to provide a way of controlling the direction of operation of a dental chuck and of controlling its rotational speed in either direction.

Another object of the invention is to provide an air turbine, low speed, high torque, dental straight handpiece having an air inlet in line with the handpiece.

Another object of the invention is to provide a simple means for reducing the relatively high speed of air turbine rotation to a lower speed more suitable for dental chuck rotation.

An additional object of the invention is to provide a dental handpiece having a chuck that is readily released externally of the handpiece housing.

A further object of the invention is to provide an air turbine handpiece that is simple, straightforward, well balanced and easily handled.

An additional object of the invention is to provide a dental handpiece that is reliable, is unlikely to become clogged and operates at a relatively cool temperature.

A further object of the invention is in general to provide a satisfactory, economical and improved dental handpiece.

Other objects together with the foregoing are attained in the embodiment of the invention described in the accompanying description and illustrated in the accompanying drawings, in which:

FIG. 1 is a plan of one preferred form of dental handpiece pursuant to the invention;

FIG. 2 is a cross-section to an enlarged scale, the plane of section being indicated by the line 2-2 of FIG. 1;

FIG. 3 is a cross-sectional view similar to FIG. 2 but taken on a plane at right angles to the plane of FIG. 2;

FIG. 4 is a cross-section somewhat similar to FIG. 3 but showing a modified form of the device;

FIG. 5 is a cross-section on a diametrical plane and to an enlarged scale showing a chuck utilized in the handpiece;

FIG. 6 is a plan of a device shown in FIG. 5;

FIG. 7 is a cross-section, the plane of which is indicated by the line 7-7 of FIG. 3;

FIG. 8 is a cross-section of a modified form of handpiece;

FIG. 9 is a fragmentary view of a speed control mechanism;

FIG. 10 is a view comparable to FIG. 9;

FIG. 11 is a cross-section on the line 11-11 of FIG. 9;

FIG. 12 is a cross-section on the line 12-12 of FIG. 9;

FIG. 13 shows a modified form of chuck arrangement;

FIG. 14 is a fragmentary plan of the device shown in FIG. 13;

FIG. 15 shows a modified form of speed regulator; and

FIG. 16 is a fragmentary plan of the device shown in FIG. 15.

In its preferred form the dental handpiece of the invention includes an outer housing 6 of a suitable and convenient configuration designed to support a dental tool 7 at one end. A flexible hose 8 is attached to a nipple 9 at the other end of the handpiece and affords a supply of compressed air at a pressure above that of the atmosphere. Preferably, the nipple 9 is at one end of a rod 13 provided with a central passage 14 having a closed end 16. The rod extends along the longitudinal axis 17 of the handpiece and is rotatable about the axis 17 and within a bore 18 formed in a plug 19. The rod 13 is held axially within the plug 19 by a screw 21 threaded into the plug and extending into a semicircular cross channel 22 in the rod so that the rod can be rotated readily through at least a half rotation. Air leakage between the rod and the plug 19 is precluded by a pair of O rings 23 and 24. The rod at its inner extremity near the closed end is provided with an angular nozzle 26 disposed to intersect the passage 14 and to diverge from the axis 17 in one direction when the rod is in one rotated position but, as shown by the dotted lines in FIG. 2, to diverge in the opposite direction when the rod is rotated through about a half turn.

The plug 19 is conveniently threaded into the housing 6 and when it is in a selected axial position is clamped or held by a tapered screw 27 (FIG. 3). The screw can be driven into an expansion slot 28 in the plug so that a tight expansive frictional engagement can be maintained between the plug and the housing.

Air from the hose 8 which travels through the passage 14 in the rod escapes from the nozzle 26 and impinges upon a turbine wheel 31 having a central hub 32 and a number of blades 33 preferably inclined with respect to the cross axis 34 of the turbine wheel. The turbine wheel runs on a cross shaft 36 rotatable about the axis 34 and carried in antifriction bearings 37 and 38 supported in wings 39 and 41 projecting from the plug 19. Conveniently, the plug has an arcuate cut-away 42 so that the turbine wheel vanes or blades pass close to the nozzle in a location to be impinged upon by the released high pressure air. The turbine wheel turns in one direction when the nozzle is pointed in one way and the other direction when the nozzle is oppositely pointed.

The turbine shaft 36 is extended by a drive shaft 46 of tapered form. Frictionally engaging the tapered drive shaft 46 is a driven cup 47 mounted on a driven shaft 48 coaxial with the longitudinal axis of the handpiece. A friction material 49 overlies the cup margin so the cup is readily driven by the shaft 46. The speed of rotation of the turbine is reduced substantially to the speed of rotation of the cup 47. The friction between the shaft 46 and the cup is adjustable by turning the plug in the housing. The cup and shaft 48 are readily supported in a pair of ball bearings 50 and 51 of the usual design. Particularly, the outer race 52 of the bearing 51 is secured in the housing 6 while the inner race 53 of the bearing carries the shaft 48.

Particularly in accordance with the invention, the bearing 51 is utilized to afford a further reduction in speed of the driving mechanism. In a tubular portion 54 of the handpiece casing 6 is mounted a ball bearing 55 supporting a final shaft 57. This shaft carries a hub 58 ending in a castellated or spider portion 59 including fingers 61 (FIG. 7) arranged to be interspersed between the balls in the bearing 51. Since the inner driving race 53 operates at the speed of the shaft 48 and since the outer race 52 is stationary in the housing 6,

the balls partake of an intermediate speed. This is transmitted by contact of the balls with the interspersed spider fingers 61 so that the shaft 57 operates at considerably less rotational speed than does the shaft 48. In effect, there are two speed reductions from the turbine 36, one through the friction drive members 46 and 49 and the other through the bearing-spider arrangement 51 and 61.

The shaft 57 is connected to the dental tool 7 in any convenient way so that when air is supplied to the unit, the operator can arrange for the tool to be driven in either of two directions merely by rotating the rod 13 from one extreme position to the other so that the nozzle 26 is changed from one direction to the other. There is a speed reduction through the friction mechanism and another one through the bearing mechanism so that the operator can derive a high torque, relatively low speed operation of the tool 7 by means of a relatively high speed reversible air turbine 36.

In some instances the two speed reductions are not needed since it may be desired to have the dental tool 7 operate at a considerably higher rate, a rate more nearly comparable to that of the turbine. In that instance, as shown in FIG. 4, the friction cup 47, while otherwise as previously described, instead of being mounted on a driven shaft 48 is rather mounted on a final shaft 66 carried in bearings 67 and 68 in the housing 69. The shaft 66, if desired, may even carry an air bushing 71 through which some air from the turbine is permitted to escape so that the shaft 66 is supported by an air bearing very close to the tool 7 in an accurate fashion suitable for high speed operation.

It is convenient to have a quick acting chuck to hold the tool 7. A special chuck can well be adapted to the arrangements shown in the preceding figures, particularly as illustrated in FIGS. 5 and 6. In this instance the outer jacket 72 suitably supports a final shaft 73 in any appropriate fashion for rotation about the longitudinal axis of the implement. The end of the shaft 73 is counterbored to provide an end chamber 74. At its outermost end the chamber holds a plug 76 having a central passage to receive the shank of the tool 7 and having a threaded engagement 77 with the shaft 73. The plug has a conical inner end 78 against which a collett 79 is pressed by a spring 81 seated in the bottom of the chamber 74. The collett is hollow inside to receive the tool 7 and has lateral slots 82 so that when the conical end 83 of the collett is urged against the conical end of the plug 76 by the spring 81, the walls of the slots are narrowed and the collett grips the tool 7.

In order that the tool may be released upon occasion, the collett 79 supports a cross rod 84 slidable in slots 85 cut in the sides of the shaft 73. A loose collar 86 surrounds the shaft and lies against the cross rod 84 and also lies against an eccentric 87 supported on a shaft 88 journaled in the housing 72. A lever 89 is fast on the shaft 88 at one end and conforms generally with the configuration of the casing 72 which has an area 90 cut away so that the envelopes of the lever and of the casing are substantially continuous. A detent 91 at one end of the lever fits into a dimple 92 in the casing so that the lever normally is centralized. When the lever is swung to either side of central position, however, it rotates the shaft 88 as well as the eccentric 87 which then urges the loose collar 86 against the cross rod 84 and moves the rod rearwardly to compress the spring and permit the otherwise unrestrained parts of the collett

79 to resume their expanded position and to release the tool 7.

The foregoing devices do not have any particular means for varying the speed of operation of the tool except by varying the incoming air pressure through a means, not shown. Since it is helpful to have a variable speed for the tool 7 under many circumstances, I provide such an arrangement in the form of the invention shown in FIGS. 8 to 12 inclusive. In this instance there is an outer casing 101 into which is screwed a plug 102 having a central bore 103 in which a tube 104 is rotatably fixed. The tube is held in place in the plug by a set screw 106 allowing the tube to be rotated a half turn, as before. The tube has a connector 107 to receive an air hose in the previously described fashion. Air leakage between the tube and the plug 102 is precluded by O rings 108 and 109. Within the tube is a central passage 111 for incoming air which is released through a nozzle 112 onto a turbine wheel 113 disposed in a chamber 114 within the housing 101.

Air entering the chamber 114 through the nozzle 112 after leaving the turbine wheel is in some instances free to escape to the atmosphere through a bleed passage 116 in the plug 102 and leading to the exterior. Flow is controlled by a collar 117 rotatably mounted on the plug 102. The collar has an air passage 118 therein. An O ring 119 precludes leakage. When the collar is in the position shown in FIG. 8 there is free exhaust of the spent air from the turbine but when the collar is rotated so that the passage 118 is out of registering position with the passage 116 there is no air escape. Intermediate positions of the collar control speed.

The turbine wheel 113, as before, has a driving shaft 121 in frictional engagement with a friction ring 122 on a driven cup 123. The cup is supported on a shaft 124 coaxial with the axis of the casing and supported by a thrust and radial bearing 125 as well as by a radial air bearing 126 and finally by a tail bearing 127 in a removable tip 128 screwed into the housing 101.

In order to control the speed at which the shaft 124 is driven there is provided on the driven cup 123 an end face 131 having radial grooves of conical configuration. Opposite the face 131 is a plate 132 with a normal surface and supported on a hub 133 slidable on the shaft 124. The hub 133 carries a bushing 134 slidable in the housing 101. The bushing 134 is pierced by a number of passages 135 (FIG. 12). The hub 133 is urged toward the left in FIG. 8 and against the conical surface 131 by a spring 136 interposed between the fixed bearing 125 and the hub 133. Interposed between the plate 132 and the cone 131 are balls 138 operating in the radial grooves 139.

When the speed of the shaft 124 is relatively slow, centrifugal force permits the balls 138 to remain in their central location but as the speed increases the balls are centrifugally driven outwardly and, acting against the conical surfaces 131, displace the plate 132 to the right in FIG. 8 displacing the bushing 134 and compressing the spring 136. Movement of the bushing 134 in an axial direction toward the right in FIG. 8 causes the edge of the bushing to override a number of radial vent holes 141 opening to the atmosphere. There is free air flow around the turbine wheel and from the chamber 114 out through the passages 135 and to the atmosphere through the vent holes 141 when the speed is slow. When the speed increases the outflying balls move the bushing 134 partly to throttle the outlet pas-

sages 141 so that air cannot readily escape. This reduces the amount of air flowing past the turbine and reduces its speed. In this fashion the turbine can be made to operate at a governed speed.

At any time when speed governance is not required the user can rotate the collar 117 so that it no longer blocks the escape passage 116 but rather opens that passage to the atmosphere. Since flow through the passage 116 is much easier than through the rest of the rather intricate air path, the governor has little or no further effect.

As shown in FIG. 13 a modified form of chuck arrangement may be employed. The drive shaft 143 is mounted near one end in a bearing 144 supported in the housing 146 and has a counterbore 147. The tool 148 extends into the counterbore between one or more pairs of gripping balls 149. Each ball is located within a conical opening 151 in a related spring finger 152. The finger is actually a part of the shaft 143 partially separated from the rest of the shaft by saw cuts 153.

Overlying the shaft 143 is a sleeve 154 having a cone 156 at one end and having a flange 157 at the other end. A spring 158 surrounds the shaft 143 and is disposed between the flange 157 and a collar 159 fast on the shaft 143. Abutting the flange 157 is an eccentric 161 or cam on a cross shaft 162 bearing in the housing 146 and secured to a lever 163 having a detent 164.

When the lever 163 is swung away from the housing, the eccentric 161 is rotated into a position retracting the sleeve 154 against the spring 158 and freeing the balls 149 so a tool 148 can be introduced or withdrawn. When a tool is in place and the lever is put into the position against the housing shown in FIG. 13, the eccentric 161 turns away from the flange 157 and the spring advances the sleeve 154 so that the cone 156 forces the balls 149 tightly to grip the tool 148 so that it rotates with the shaft 143.

As a modified way of regulating the speed of the driven shaft, as shown in FIG. 10, there is provided a construction in which the driven cup 123 is connected to the driven shaft 124, as before. Balls 138 are speed responsive and move outwardly as the shaft speed increases. As they move outwardly the balls press a plate 166 to the right. A hub 167 on the plate then compresses the spring 136 abutting the bearing 125.

When a maximum selected speed has been attained, the plate 166 has been moved axially far enough to engage a friction disc 168 having a bearing 169 on the hub 167 but restrained by one or more radial rods 171 engaging the housing 146. Each of the rods is impelled by the rotation of the parts to lodge at the end of a related helical slot 172 in the housing and so holds the disc 168 against turning and in proper braking position for the speed selected. If the user desires no braking and prefers to let the turbine run free, he moves the rods to the opposite end of the slots 172, past a detent 173. This moves the disc 168 to a different axial posi-

tion out of range of the plate 166 and affords no friction braking.

What is claimed is:

1. A dental handpiece comprising a tubular housing having a longitudinal axis, a drive shaft, means for supporting said drive shaft in said housing for rotation about said axis, a dental chuck, means for connecting said chuck to said drive shaft, a friction disc mounted on said drive shaft for rotation about said axis, an air turbine, means for mounting said air turbine in said housing for rotation about a transverse axis normal to said longitudinal axis, a friction shaft connected to said turbine and engaging said friction disc, and means for supplying said turbine with air.
2. A device as in claim 1 in which said air supplying means is a rod rotatable in said housing about said longitudinal axis.
3. A device as in claim 2 in which said rod has an air passage therein terminating adjacent said air turbine in a nozzle extending at an angle to said axis.
4. A device as in claim 1 in which said means for supporting said drive shaft includes a ball bearing having spaced balls and said means for connecting said chuck to said drive shaft includes a spider having prongs disposed between said balls.
5. A device as in claim 4 in which said ball bearing has an outer race fixed in said housing and has an inner race fixed on said drive shaft.
6. A device as in claim 1 in which said housing includes a port for exhausting air therefrom, and means for throttling air flow through said port.
7. A device as in claim 6 in which said port is through said housing normal to said longitudinal axis and said throttling means is a sleeve slidable along said axis.
8. A device as in claim 6 including an additional port for exhausting air from said housing, and means for manually opening and closing said additional port.
9. A device as in claim 6 including means responsive to the speed of rotation of said drive shaft for operating said throttling means.
10. A device as in claim 9 in which said speed responsive means includes a cone on said friction disc, a hub slidable on said drive shaft and carrying said throttling means, a plate on said hub opposite said cone, a spring urging said plate and said cone together and balls between said cone and said plate.
11. A device as in claim 1 in which said means for connecting said chuck to said drive shaft includes means defining a conical surface adjacent the end of said drive shaft, said chuck is slidable toward and away from said surface, a cross shaft engaging said chuck is slidable in slots in said drive shaft, a collar is slidable around said drive shaft, a spring urges said cross shaft against said collar, a lever is disposed to swing on the exterior of said housing, and means operated by said lever positions said collar on said drive shaft.
